United States Patent Office

Des. 204,124
Patented Mar. 15, 1966

204,124

CHAIN SAW

Paul Olney Rawson, Jr., Trumbull, and Peter D. George,
Stratford, Conn., assignors, by mesne assignments, to
Textron, Inc.

Filed Sept. 11, 1964, Ser. No. 81,683

Term of patent 7 years

(Cl. D93—3)

FIG. 3

FIG. 4

FIG. 5

FIG. 1 is a left perspective view of a chain saw showing our new design.

FIG. 2 is a right perspective view thereof;

FIG. 3 is a front elevational view thereof;

FIG. 4 is a rear elevational view thereof;

FIG. 5 is a bottom plan view thereof; and

FIG. 6 is a left perspective view of another embodiment of our design, the sole difference residing in the handle structure, parts being fragmentarily shown for convenience of illustration.

We claim:

The ornamental design for a chain saw, as shown and described.
